(57) **CLAIM**

The ornamental design for a combined phone screen film sticking tool and phone holder as shown and described.

DESCRIPTION

FIG. 1 is a perspective view of a combined phone screen film sticking tool and phone holder showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.

The broken lines in the drawings depict portions of the combined phone screen film sticking tool and phone holder that form no part of the claimed design.
